UNITED STATES PATENT OFFICE.

GEORGE GARTLING, OF LOS ANGELES, CALIFORNIA.

CHAIN PUMP.

Application filed June 30, 1919. Serial No. 307,795.

To all whom it may concern:

Be it known that I, GEORGE GARTLING, a citizen of the United States, residing at Los Angeles, in the county of Los Angeles and State of California, have invented a new and useful Chain Pump, of which the following is a specification.

This invention relates to valveless chain pumps and it may be said to consist in the provision of the new and novel features and in the improved construction, combination and arrangement of parts, the purposes of which will be apparent to those skilled in the art from a consideration of the preferred form of apparatus herein shown, described and claimed.

This chain pump is similar in construction and operation to the cable pump described in my application for Letters-Patent on cable pump, filed Aug. 18, 1919, Serial Number 318,401, in that the inverted cone shaped shoe obstructs the passage of large rocks or gravel from entering the pump cylinder.

One of the principal objects of this invention is to provide an endless chain pump that will be especially effective in operation, cheapness of construction, easily assembled and repaired and which will be exceptionally strong and durable.

Another object of the invention is to provide an endless chain pump that is especially adapted for operation in wells having mud or hard sand therein as means are provided for practically eliminating the wearing action of these substances on the movable contacting parts of the pump.

Another object of this invention is to provide a chain pump with buckets that are of less diameter than the main portion of the pump pipe so that the buckets in the endless chain will contact only with the wall of the suction barrel.

Another feature of this invention is shown in the novel construction of the buckets that are formed without packing that is common in bucket construction.

Another novel feature is shown in the means for mounting the driving shaft; and

also the means connected therewith for increasing or decreasing the tension on the pump chain.

Other objects, features and advantages of the invention may appear from the accompanying drawing, the subjoined detailed description and the appended claims.

The drawing illustrates the invention.

Figure 1 is a central vertical section through a pump embodying the elements of this invention and with parts shown in operating position in a well; also showing the center portion of the well and pump broken away.

Fig. 2 is an enlarged sectional view on the line x^2 of Fig. 1 showing the upper portion of the pump and associated parts.

Fig. 3 is an enlarged view of one of the buckets attached to the endless chain, also showing by dotted line a portion of the pump cylinder.

Fig. 4 is another enlarged view of a bucket and chain attachment; also showing the pump cylinder by dotted lines.

Fig. 5 is an enlarged plan view of one of the buckets detached from the endless chain.

In detail the chain pump 1 has at its upper end the hollow stand 2 that is secured by the anchor bolts 3 to the cement platform 4.

In one side of the stand 2 there is an opening 5 through which there is extended the spout 6, that is integral with the upper end of the pump pipe 7.

The spout 6 and pump pipe 7 can be held in place relative to the stand 2 and opening 5 by any well known means. As herein shown the pipe 7 has oppositely extending flanges 8 and 9 that are secured by the bolts 10 to the stand 2.

The upper end of the stand 2 has thereon the flange extension 11 to which is secured by the bolts 12 the top covering 13; and central in the covering 13 is the hole 14 through which hole there is extended the bolt 15. The bolt 15 has its lower end integral with the cylindrical bearing block 16, which block is slidably mounted in the stand 2.

The bolt 15 is threaded and has attached

thereto the nut 17 by which nut and bolt the bearing block 16 is raised or lowered in the stand 2.

To the lower end of the bearing block 16 there are secured by the straps 18 the bushings 19, which bushings extend beyond the periphery of the block 16 and through the slots 20 and 21 in the wall of the stand 2; and in the bushings 19 there is loosely mounted the shaft 22. To one end of the shaft 22 there is secured the pulley 23 which pulley is driven from some source of power not shown. By means of the extension of the bushings 19 into the slots 20 the shaft 22 is prevented from turning and contacting with the sides of the slots 20 when power is applied to the pulley 23.

Secured about midway of the shaft 22 is the sprocket wheel 24 which wheel is adapted to drive the endless chain 25.

The chain 25 is mounted on the sprocket wheel 24 and also on the sprocket wheel 26 that is mounted on the shaft 27 at the bottom end of the pump. The shaft 27 has its bearings in the walls of the shoe 28, one of which bearings is shown by dotted lines in Fig. 1. These bearings are of common construction and are not shown in detail.

The shoe 28 is of slightly less diameter than the inside diameter of the well casing 29; or so that the shoe 28 can be passed into the well casing 29 in a sliding fit when placed in pumping position.

The lower end of the shoe 28 has the wall thereof converging into an inverted cone 30 in which are a plurality of small holes 31; which openings give a free passage to the water, but obstructs the passage of large rocks or gravel to the pump cylinder.

The upper end of the shoe 28 is open for the purpose of providing a downward passage of the chain 25 except that at one side of the cylinder the wall is contracted into a threaded stem 32 to which stem is secured the lower end of the pump cylinder 33 and the opening through the stem 32 is substantially the diameter of the opening through the suction barrel.

The upper end of the suction barrel 33 is detachably secured to the lower end of the pipe 7; and as is seen in Fig. 1 the diameter of the pipe 7 is greater than the diameter of the suction barrel 33; the purposes of which will be hereafter explained.

The buckets 34 are disks that are formed with a spherical periphery; that is the disks are the contour of a sphere with opposite portions cut away.

In Fig. 4 the outline and radius of the sphere are indicated by the dotted lines; and as seen therein the periphery of the disk lies within the periphery of an imaginary sphere; also as seen in the drawing the oppositely disposed flanges 35 and 36 have a

portion of their outer surfaces lying within 65 the outline of the sphere.

The purposes of the flanges 35 and 36 are to guide the disks or buckets 34 as they enter the opening through the stem 32 and to keep the buckets from binding as they travel 70 through suction barrel.

From the foregoing it can readily be seen that only a small portion of the periphery of the disks or buckets 34 contact with the wall of the suction barrel 33; and also that 75 these buckets never contact with the pipe 7, consequently the frictional engagement of the buckets with the pump wall is reduced to a minimum. Also the spherical periphery of the disks prevent sand or mud from accumulating on the rim of the disk as they pass under the wheel 26 and approach the opening through the suction barrel.

There are cast integral with the disks 34 the chain link connections 37 and 38 which 85 parts are adapted to join the links of an ordinary sprocket chain; by means of which connections the disks are easily and quickly secured in place or removed for replacing when too badly worn to perform their function.

The suction barrel 33 and also the disks 34 are case hardened steel so that they will resist the wear of fine sand.

It is intended however that the suction 95 barrel is a greater hardness than the disk as the latter are easily removed for replacing.

The real lift of the water 39 is in the suction barrel 33 in which the periphery of the 100 disks 34 snugly contact with the inner wall of the suction barrel; and the disks 34 are attached to the chain 25 at predetermined distances so that always one or more of them are within the suction barrel. In other 105 words before the disk or bucket *a* has passed out of the suction barrel 33 the bucket *b* will enter.

While it is true that the real lift of the water 39 is primarily accomplished by the 110 buckets in the suction barrel 33 the other buckets also perform a lifting function; for as water is non-compressible and as the space below each bucket from the pump cylinder to the top spout is filled with water 115 when the pump is in operation the water cannot escape through the clearance between the buckets and the wall of pipe 7, but must travel upward with the buckets so that the lift is distributed and not thrown entirely on the buckets in the suction barrel; and also the wear on the buckets is thereby limited to their short movement through the pump cylinder.

The sprocket wheels 24 and 26 have the 125 usual cutaway portions 40 and 41 to make a clearance for the buckets 34.

By means of the bolt 15 and nut 17 the

- bearing block 16 can be lowered to loosen chain 25 when old worn buckets are to be replaced with new ones; and also that parts be returned to operating position.
- 5 In operation the pump 1 is placed in position as heretofore described and power applied to the pulley 23 to rotate the sprocket wheel 24 in the direction of the arrow shown in Fig. 1; which rotation of the pulley will move the chain 25 and its associated parts to lift the water from the bottom of the well through the suction barrel and pipe 7 to the top of the pump where the water will discharge by gravity from the pump spout.
- 10 While I have described my apparatus as operating with a chain I do not wish to be limited to any specific connection between the buckets, as a cable or other connection can be used equally well.
- 15 I claim.
1. In a pump, a platform; a well casing attached to said platform and extending downward in a well; a stand secured to said platform; a pipe secured to said stand, said pipe extending downward in said well casing; a hardened metallic suction barrel having its upper end removably attached to the bottom end of said pipe, the opening through said suction barrel being of less diameter than the opening through said pipe; a shoe attached to the lower end of said suction barrel, said shoe having a cylindrical wall that is a sliding fit within said well casing; an endless sprocket chain mounted in said stand and shoe; hardened metallic disks detachably connected to said sprocket chain, said disks formed with spherical peripheries; and means for rotating said sprocket chain for the purpose specified.
- 20 2. In a pump, a platform, a stand secured to said platform, a well casing secured to said platform, a cylindrical block in said stand, a power driven shaft extending through said stand and mounted on said block, a sprocket wheel secured to said shaft, a shoe in said well casing in which another sprocket wheel is mounted, said shoe having a cylindrical wall that is a sliding fit within said well casing, a pipe connection between said shoe and said stand, an endless sprocket chain on said sprocket wheels, said chain passing upward through said pipe, and buckets on said chain.
- 25 3. In a pump, a platform, a stand secured to said platform, a well casing, a shoe within said well casing and having a cylindrical wall that is a sliding fit within said casing, a cylindrical bearing block in said stand, a power driven shaft mounted on one end of said block and extending through said stand, a sprocket wheel on said shaft, a sprocket wheel in said shoe, a sprocket chain having buckets thereon that are mounted on said sprocket wheels in position to pass through a pipe connecting said stand with said shoe, and means for raising or lowering said bearing block to tighten or loosen said sprocket chain.
- 30 4. In a pump, a platform, a stand secured to said platform, a pipe secured to said stand, said pipe extending downward in a well, a bearing block in said stand said bearing block having bushings extending through slots in the wall of said stand, a power driven shaft journaled in said block, said shaft extending through the bushings and said stand, a sprocket wheel on said shaft, a shoe having its lower end converging into an inverted cone and having perforations therein, said shoe being secured below said pipe, a sprocket wheel in said shoe, an endless sprocket chain on said sprocket wheels, buckets on said chain, a rod connected to said bearing block, said rod extending upward through said stand, and means connected with said rod for raising or lowering said bearing block for the purpose specified.
- 35 5. In a pump, a platform, a well casing attached to said platform, a pump stand secured to said platform, a pipe having its upper end attached to said stand and extending into said well casing, a suction barrel having its upper end detachably connected to the lower end of said pipe, a shoe detachably connected to the lower end of said suction barrel, said shoe having a cylindrical wall that is a sliding fit within said well casing, a perforated inverted cone integrally connected to the cylinder of said shoe, and chain and bucket means for lifting water from below said cone by suction and discharging it at the upper end of said pipe.
- 40 6. In a pump, a platform, a well casing attached to said platform, a pump stand, a pipe having its upper end detachably attached to said stand, a shoe provided with a top open to said well casing and one side of which is contracted into a stem, said stem being detachably connected to the lower end of said pipe, said shoe having a sliding fit with said well casing and the lower end thereof converging into an inverted cone, said inverted cone being provided with a plurality of holes for the purpose as set forth.
- 45 7. A chain pump comprising a pump stand, a well casing, a pipe having its upper end detachably connected to said stand, a shoe having a top open to said well casing and detachably connected to the lower end of said pipe, said shoe converging into an inverted cone at its lower end, and said cone having a plurality of openings adapted to allow water to enter said shoe and obstruct the passage of large rocks or gravel to the operating parts of the pump, a suction

barrel, sprocket wheels mounted in said shoe and said stand, and a chain having buckets thereon and adapted to cause water to pass through said shoe, pipe and stand.

- 5 8. A chain pump comprising a chain having buckets thereon, sprockets on which said chain is mounted, a well casing, a stand, a pipe having its upper end detachably attached to said stand, a shoe having a top open 10 to said well casing and being detachably attached to the lower end of said pipe, said

shoe having its lower end terminating in an inverted cone having perforations therein, and said shoe being adapted to receive one of said sprockets for the purpose set forth. ¹⁵

In testimony whereof, I have hereunto set my hand at Los Angeles, California, this 23rd day of June, 1919.

GEORGE GARTLING.
